UNITED STATES PATENT OFFICE.

WILLIAM J. BARBER, OF CLEVELAND, OHIO, ASSIGNOR, BY MESNE ASSIGNMENTS, TO THE KLINE COMPANY, OF CLEVELAND, OHIO, A CORPORATION OF OHIO.

GAS-BURNER.

1,342,617.

Specification of Letters Patent.

Patented June 8, 1920.

Application filed July 7, 1919. Serial No. 309,250.

To all whom it may concern:

Be it known that I, WILLIAM J. BARBER, a citizen of the United States, residing at Cleveland, in the county of Cuyahoga and State of Ohio, have invented certain new and useful Improvements in Gas-Burners, of which the following is a specification.

The invention herein consists in a burner designed more especially to be used in heating furnaces of the kinds usually employed in residences and dwelling apartments and which are of the hot air, steam or hot water style or type, and the installation may comprise or use one or more of the burners or burner units shown.

In the accompanying drawings, Figure 1 is a plan view of a two burner combination, and Fig. 2 is a side view of Fig. 1. Fig. 3 is a cross section of Fig. 1 through opposite combustion tubes therein. Fig. 4 is a longitudinal section of a burner pipe through the inclined orifices therein.

In an installation of this style of burners I may employ one or more complete burners or burner units, and which consist each of a straight pipe 2 and two or more sets of combustion tubes 3 seated over orifices in the said pipe at an inward inclination toward each other lengthwise of the pipe of about forty-five degrees and which brings said tubes at right angles to each other. The said orifices also are shown as inclined toward each other from group to group in the same longitudinal line, but inclined away from each other in the same group. The tubes in each set or pair of orifices are limited to two, and are cast integral with a ring or band shaped base 6 sleeved upon the pipe 2 and adapted to be adjustably fixed thereon over said orifices by means of set screws 4. This provides for both longitudinal and rotary movement of the burner tubes and which is necessary to place the said tubes in right working relations with each other and over the orifices 6 when the burners are assembled.

The said burner tubes 3 are believed to be original in these further particulars, that they are straight cylindrical members having preferably two opposite air inlet openings or recesses 5 at their base and open full width at their outer ends. The feature of length of the said tubes also is material because each tube becomes a mixer in and

for itself, and a fair length is necessary to 55 promote such mixing, and with a plurality of burner units employed together in a furnace the said tubes require at least the relative length shown to bring their discharge into such relatively near working relations 60 that the best possible combustion may ensue at the confluence thereof, say about as shown in the middle portion of Fig. 1, where four converging tubes are set to commingle their discharge at a common center. However, 65 as to this feature or arrangement of the said tubes, it will be noticed at the sides of the burner units where only two tubes are shown, the discharges therefrom traverse each other at right angles exactly as occurs 70 where four such tubes are used, and effective commingling of the gases and of combustion is assured. A common supply pipe 8 is provided for all the burner units, and each unit has its own valve V, so that one 75 or more may be used as temperature conditions may demand.

From the point of view of a single burner unit constructed as herein shown, a complete working unit would be made by the 80 use of only two combustion tubes on each pipe positioned and related as seen in Fig. 2, and this may be said to be the basic generic conception, but which is amplified and improved by the use of two units having 85 four several burner tubes disposed to unite and combine their discharge on a given center and adapted to sustain a single flame at their confluence. This doubles up the more limited conception of only two combustion 90 tubes and gives what is shown in Fig. 1, with the outer combustion tubes on the two pipes 2, omitted but which makes a thoroughly practical burner.

What I claim is:

1. In gas burners for heating furnaces, a burner unit comprising a pipe with a plurality of orifices on the same line longitudinally and spaced apart, and burner tubes seated on said pipe over said orifices and inclined toward each other at such angle as will bring the discharge from their ends into confluence midway between the ends of said tubes.

2. In gas burners, a pipe having a plurality of orifices in the same line longitudinally, rings adjustably sleeved on said pipe having openings over said orifices and

burner tubes seated on said rings over said openings and inclined toward each other at approximately 45° angle of inclination.

3. In gas burners, a burner unit comprising a pipe with orifices lengthwise at intervals, a burner tube seated over each orifice and means supporting the tubes on said pipe adapted to adjust the tubes in respect to the orifices covered thereby, and said tubes inclined toward each other at about forty-five degrees angle and apart at their ends.

4. In gas burners, a burner unit comprising a pipe having two rows of orifices longitudinally disposed in pairs transversely of the pipe, and burner tubes seated over said orifices and inclined away from each other

in each pair and toward each other in each row from pair to pair.

5. In gas burners, a gas supply pipe and two burner pipes parallel to each other supported on said supply pipe and provided with orifices spaced apart in the same line longitudinally, and combustion tubes seated over said orifices at an inward inclination 25 between said burner pipes and inclined toward each other on each pipe, thereby conveying the discharge of all the said combustion tubes to a given center.

Signed at Cleveland, in the county of 30 Cuyahoga, and State of Ohio, this 12th day of May, 1919.

WILLIAM J. BARBER.
